BIAS-CUTTING MACHINE

Edward B. Case, St. Louis, Mo.

Application June 9, 1943, Serial No. 490,135

36 Claims. (Cl. 164—61)

The present invention relates generally to cloth cutting machines and, more particularly, to a certain new and useful improvement in machines specifically adapted for cutting cloth on the bias.

My invention has for its principal object the provision of a machine for cutting tubular or tubiform cloth of heavy or light weight on the bias, the machine embodying unique mechanism for obtaining accurate widths of bias-cut cloth without stretching and then winding the same in a uniformly tensioned roll again without any stretching of the cloth.

My invention has for a further object the provision of a bias-cutting machine having unique cloth delivering mechanism, whose rate of travel may be facilely synchronized with all other moving parts of the machine, the machine also including unique means whereby the approximate predetermined rate of delivery travel for a selected width of bias-cut material or a selected or desired angularity of bias may be visually disclosed to the operator.

My invention has for another object the provision of a bias-cutting machine having a cutting assembly readily adjustable for varying the bias-angle of the cut cloth, the machine being also characterized by the inclusion of unique mechanism for winding the bias-cut cloth in rolls uniformly tensioned throughout and readily removable from the machine for convenient use.

My invention has for still another object the provision of a bias-cutting machine embodying unique means for delivering the goods on the straight to the cutting assembly, then effecting a cutting on the bias of the fed cloth, and then, without interruption, advancing or delivering the bias-cut cloth to winding rolls located in spaced relation from, and disposed in angular relation to the path of travel of the straight cloth to, the cutting mechanism. The delivery mechanism, I may here state, is preferably characterized by the inclusion of an endless belt capable of performing the dual function of (1) drawing the uncut cloth in the form of a tube spirally along an expanding stationary mandrel until the cloth is acted upon by the cutter and then, as mentioned, (2) carrying the cut cloth to wind-up mechanism disposed at a selected angle oblique to the mandrel, the machine being capable of efficiently producing bias-cut cloth of either heavy or light weight without stretching the material in any direction.

And with the above and other objects in view, my invention resides in the novel features of

form, construction, arrangement, and combination of parts presently described and pointed out in the claims.

In the accompanying drawings,

Figure 1 is a plan view of a bias-cutting machine embodying my invention;

Figure 2 is a side elevational view of the forward portion of the machine;

Figure 3 is an enlarged detail sectional view of the machine taken approximately on the line 3—3, Figure 1;

Figure 4 is a side elevational view of the rear portion of the machine, as indicated by the line 4—4, Figure 1;

Figure 5 is an enlarged rear elevational view of the machine, as indicated by the line 5—5, Figure 1;

Figure 6 is an enlarged side elevational view of the rear portion of the machine opposite to that shown in Figure 4, as indicated by the line 6—6, Figure 1;

Figure 7 is an enlarged detail longitudinal sectional view of the machine taken approximately on the line 7—7, Figure 1;

Figure 8 is a like view taken approximately on the line 8—8, Figure 7;

Figure 9 is a detail view of one of the mandrel bearings of the machine;

Figure 10 is an enlarged side elevational view of the forward end of the machine, as indicated by the line 10—10, Figure 1;

Figure 11 is a detail sectional view approximately on the line 11—11, Figure 10;

Figures 12 and 13 are enlarged end and side elevational views of the machine, as indicated by the lines 12—12 and 13—13, respectively, Figure 1;

Figure 14 is a further enlarged detail sectional view approximately on the line 14—14, Figure 13;

Figure 15 is a horizontal sectional plan view of the machine taken on a plane just below the upper rails of the machine-framework and approximately at the central region of the machine;

Figure 16 is a reduced transverse sectional view of the machine taken approximately on the line 16—16, Figure 15;

Figure 17 is an enlarged plan view of the forward portion of the machine;

Figure 18 is a transverse sectional view taken approximately on the line 18—18, Figure 17;

Figure 19 is an enlarged fragmental plan view, partly in section, of the machine;

Figure 20 is a horizontal plan view, partly in

section, taken approximately on the line 20—20, Figure 2;

Figures 21, 22, 23, and 24 are detail sectional views taken approximately on the lines 21—21, 22—22, 23—23, and 24—24, respectively, Figure 20;

Figure 25 is a fragmentary elevational view, illustrating, on an enlarged scale, some of the mechanism employed for elevating a belt tensioning-bar;

Figure 26 is an enlarged plan view of the central portion of the machine;

Figures 27 and 28 are enlarged sectional views taken on the lines 27—27 and 28—28, respectively, Figure 26, the cloth-tube for bias cutting being shown also in Figure 27;

Figure 29 is a fragmental detail view of the rotary cutting knife assembly of the machine;

Figure 30 is an inverted plan view illustrating the cutting knife assembly; and

Figures 31 to 37, both inclusive, are so-called diagrammatical views illustrating the successive steps in a bias-cutting operation as effected by the machine of my invention.

Referring now more in detail and by reference to the drawings, which illustrate a preferred embodiment of my invention, the machine includes, briefly stated, a suitable rigid main stationary framework or base A, a cloth-tube supporting mandrel B, cloth-tube unwinding mechanism C, a cloth-cutting assembly D, means, generally indicated E, for controlling and indexing the cloth-unwinding mechanism C, and means, generally designated K, for winding the bias-cut cloth-strips into roll form. A second or auxiliary framework, generally designated F, adjustable angularly relatively to the base or main framework A about a pivot-pin G, is supported for movement on corner-rollers 93, as more fully presently appears, and mounted for travel on the framework F, is an endless belt, generally, with its associated parts or members, designated H, the framework F also supporting the rolls comprising the cloth-winding mechanism K and gearing L, whereby the belt H and rolls are driven from a suitable source of power, such as a motor M, as best seen in Figures 4 and 15.

A brief preliminary description now of the function and purpose of the machine may facilitate and enable a clear understanding of its structure and co-operative parts. For such purpose, reference is made particularly to Figures 31 to 37, both inclusive.

Figure 31 illustrates a bolt of cloth a which is to be cut on the bias, the woof and warp of cloth a being initially on the straight, as is well understood. The cloth a is accordingly first unrolled, folded over longitudinally upon itself, and then stitched, as at s, along its slightly overlapped margins a'—a', and thereby put into tubular form a'', illustrated in Figure 32. Obviously, if the cloth to be acted upon has been woven in tubular form, the stitching s is dispensed with.

The cloth-tube a'' is now layer-wise arranged in a bin 13 of the unwinding mechanism C, and its free end disposed for tube-feeding on the mandrel B, as is illustrated in Figure 33. The tube a'' is now shifted by the endless belt 146 along the mandrel B to the cutter assembly D, the rotary cutting blade 116 of which, as shown in Figure 34, is positioned obliquely to the direction of tube-feeding.

The endless belt assembly H, which parallels the cutting blade 116, carries the now bias-cut

cloth a' forwardly to the winding mechanism K, Figures 35 and 36, with the result that the roll of cloth a initially on the straight, shown in Figure 31, becomes the roll of cloth a' on the bias, illustrated in Figure 37.

Reverting now to the machine proper, the main framework A includes a pair of upper and lower rails 1 and 2, respectively, suitably joined at intervals by uprights 3 having laterally extending feet or flanges 4 for securement to a foundation or other support. At their left-hand end, as viewed in Figure 1, the rails 1, 2, are welded or otherwise secured to a fixed standard 5, to and upon the upper face of which is suitably welded or otherwise secured the supporting structure of the mandrel B, such supporting structure, in turn, comprising opposed channel bars 6 extending longitudinally of framework A and braced and held together by a plurality of cross-rods 7. As indicated at 8, two of the component channels 6 end short of the right-hand end of the mandrel B for reducing weight, desirable since the mandrel supporting frame itself is unsupported at the right beyond a diagonally disposed brace member 9 located as far to the right of the left end of base A as feasible.

As shown in Figure 2, the upper rails 1 of base A terminate short of the lower rails 2 and support a rectangular table 10, upon which the cloth-tube a'' may travel from the feeding apparatus C to the mandrel B, the extended lower rails 2, as best seen in Figure 20, being joined at their forward end by a transverse rail 2'.

The unwinding apparatus C includes a preferably circular turntable 11 provided upon its upper face with fixed blocks 12 suitably arranged for detachably engaging the bin or container 13 for the cloth to be cut. As illustrated particularly in Figures 20, 23, and 24, the turntable 11 is supported primarily on a bolster 14 fixed to the lower frame-rails 2 and provided centrally with a bearing-plate 15 for co-operation with a companion bearing 16 fixed to and upon the under side of the turntable 11, a pivot pin 17 having threaded engagement at its upper end in the member 16 and loosely projecting through registering apertures 18, 18', respectively, in the bolster 14 and in a sub-bolster 19 also rigid with the frame-rails 2. Preferably, it may be mentioned, the turntable 11 is additionally supported for facile turning movement by interposed rollers 20 mounted in brackets 21 fixed to end-rail 2' and to the sub-bolster 19, as shown. Thus the turntable 11 is supported centrally and also at intervals near its periphery, so that its turning velocity, by means presently described, may be readily controlled or regulated.

It also may be stated here that rotary travel of the turntable 11 is effected by a suitable roller 22 keyed or splined to a longitudinal shaft 23 mounted for rotation in bearings 24 provided on transverse bars 25 secured at spaced intervals to the frame-rails 2.

As presently appears, the shaft 23 is driven by the motor M, and while the speed of the motor driven roller 22 is constant, the speed of rotation imparted thereby to the turntable 11 may be varied by shifting the roller 22 toward or from the center of the turntable 11, as will be well understood, and it may be here noted that, in the operation of the machine, the cloth-tube a'' advances spirally along the mandrel B. Consequently, the unwinding mechanism C must be synchronized with the rate of speed at which the cloth advances along the mandrel, in order to

obtain paramount results. The means E, whereby such synchronization is obtainable, will now be described.

With particular reference to Figures 1, 12, 13, and 14, a suitable plate 26 supported horizontally on base A has inscribed thereon graduations 27 for indicating or designating the approximate speed required of the unwinding mechanism C for a selected bias angle. As has been stated, the framework F may be pivotally shifted to the right or to the left about the pivot G for varying such angle. It is to be noted, however, that such variation requires a variation also in the rate of unwinding and in the angularity of the cutting assembly D.

A pointer 28, fixed to and upon the upper end of a vertically disposed shaft 29, in conjunction with the graduations 27, functions to inform the operator that the unwinding rate is in approximate synchronization with the rate of movement of the winding mechanism K and cutter assembly D, the approximate unwinding speeds required for various bias angularities, as indicated by the graduations 27, it being understood, having been predetermined mathematically.

Due to variations in widths of cloth to be cut, minute adjustments between such speeds frequently become necessary, and such adjustments may be conveniently made by the operator by the means best seen in Figure 14. As there shown, fixed to shaft 29, is a worm gear 30, which meshes with a worm 31 on a shaft 31' provided with a manually engageable knob 32 and supported for rotation in a substantially channel-shaped member 33. Adjacent its lower end, shaft 29 is provided with a fixed collar 34, which rests on a bearing 35 secured to a frame-rail 2, and fixed on shaft 29 at its lower extremity, is a sheave 36 permanently connected, in turn, by a flexible member 37, to the rear end of a bar 38 which extends from the unwinding apparatus C to the control apparatus E, so that rotary motion imparted to shaft 29 will shift the bar 38 to the right or left in conjunction with means, now to be described, which forms part of the unwinding apparatus C, and which is illustrated particularly in Figures 20 and 21.

Secured at one end to the other or forward end of the bar 38, is a flexible member in the form of a suitable cable or chain 39 reeved around sheaves 40 and 41 and secured at its opposite end to a horizontally disposed plate 42 endwise shiftable in a slideway 43 fixed to a horizontally disposed platform 44, in turn, secured to the lower rails 2 of base A, as shown.

Suitable coil springs 45, anchored at one end upon platform-pins 46 and at their other end to slide or plate pins 47, function at all times to yieldingly shift the slide 42 to the left and against an angular stop 48 fixed to the slideway 43. Obviously, therefore, the springs 45 yieldingly maintain the chains or other flexible members 37 and 39 taut, so that manipulation of the worm-gear 30 will shift the slide 42 either to the right or to the left, and hence roller 22, which is splined or keyed to shaft 23 intermediate upstanding angular brackets 49 fixed to the slide 42, may be selectively shifted toward or from the center of the turntable 11 for increasing or diminishing the speed of rotation thereof.

Now, since difficulty might be encountered in shifting the driving roller 22 with the weight of the turntable 11 thereon, a treadle 50 and its associated parts permit the operator to elevate the turntable 11 for making such speed adjust-

ments while the machine is not in operation and for slowing down and eventually stopping unwinding. In such connection and referring particularly to Figures 12 and 13, it is noted that treadle 50 is located in proximity to the adjusting knob 32 and that the free end thereof is yieldingly maintained in an elevated position by means of a suitable spring 51 attached to a cross-brace 52. A chain or other flexible member 53 attached at an end to the treadle 50 and reeved over a sheave or pulley 54 mounted on the cross-brace 52 and under a similar sheave 55 mounted on the base A, as shown, is secured, as at 56, to the forward end of a shiftable bar 57, similar and parallel to, and located directly above, the bar 38. At its other or rear end, bar 57, Figure 20, is provided with a horizontally disposed pin 58, to which is fastened a chain or other suitable flexible member 59, as well as also a coil spring 60 and another chain or flexible member 61, the bars 38 and 57 being supported at intervals along the length of base A by the arrangement detailed in Figure 22 and designated 62.

Member 59 passes over a sheave 63 mounted, as shown, on bolster 14, and is secured, as at 64, to the free end of an obliquely disposed suitably elongated plate 65 hinged, as at 66, to a bracket-plate 67 fixed suitably on the frame A. Normally, whether the machine be idle or in operation, plate 65 rests at its free end upon the floor or foundation, a slight clearance obtaining therebetween and the rounded lower extremity of turntable pivot pin 17, Figure 24.

It may be here stated that the spring 60, anchored, as at 60', to base rail 2, has two functions, in that the spring 60 normally yieldingly maintains the plate 65 in its position illustrated in Figure 24, and, in addition, yieldingly maintains the free end of an auxiliary treadle 68 in an elevated position, see also Figure 23, the latter enabling the operator to elevate the turntable 11 and thereby prevent further unwinding of the material, in substantially the same manner as 45 may be accomplished by use of treadle 50.

In other words, depression of either treadle 50 or treadle 68 causes the turntable 11 to be elevated. The auxiliary treadle 68, however, it will be understood, is not essential and may, with member 61 and sheaves 69 and 70, be eliminated without in the slightest impairing the operation of the machine.

Thus the approximate rate of unwinding required for a desired width of bias-cut material is readily obtainable. The operator depresses treadle 50, consequently elevating turntable 11 out of contact with roller 22, manually rotates knob 32 until pointer 28 indicates the proper graduation 27, and thereupon releases the treadle 50. If, during machine operation, the rate of unwinding does not synchronize perfectly with the moving parts of the machine, minute adjustments may be effected merely by actuations of the knob 32 and without stopping the machine.

Since, as previously noted, the cloth-tube a'' to be cut advances spirally toward the cutter D, for reasons presently stated, the importance of maintaining the cloth-tube a'' prior to engagement upon the mandrel B in an untwisted condition is evident. By arranging the tube a'' in the bin 13 on the turntable 11 in the manner shown in Figure 33, and by rotating the turntable 11 in a counter-clockwise direction while the advancing tube a'' spirals in a clockwise direction, any twisting at the source of supply

is obviated, provided the speed of the turntable 11 has been properly regulated.

It should be noted at this time that the unwinding apparatus C functions in conjunction with other moving parts of the machine, presently described, that is to say, the unwinding apparatus C has the duty of constantly supplying the mandrel B and tubing a'' in proper quantity and in untwisted form. Once the tubing a'' has progressed along mandrel B to a point where the tube a'' reaches the cutting blade of assembly D, the tube a'' is then continuously drawn toward the cutting assembly D and thence carried to the wind-up mechanism K by the endless belt assembly H.

Rotation of the roller 22 is effected by the means or mechanism best seen in Figures 4, 15, and 16. As there shown, fixed upon the end of shaft 23 remote from the turntable 11, is a sheave 71, driven by an endless chain, cable, or the like 72 passing over a pair of pulleys 73 suitably mounted for rotation on a plate 74 forming part of frame A and through which shaft 23 passes. The flexible member 72 also passes over a spool or sheave 75, mounted for rotation, as best seen in Figure 16, upon the frame F, and also over a sheave 76 shiftably supported in a slotted bracket 76' also fixed to frame F. Anchored to the frame F and to a plate 77, is a suitable spring 78 for yieldingly maintaining the flexible member 72 taut at all times.

The member 72 is reeved over, and driven by, a pulley 79 fixed to a cross-shaft 80 mounted in bearings 81 on framework F, the shaft 80, in turn, being driven by a pulley-and-belt 82 driven by a pulley 83 fixed to a second cross-shaft 84 mounted in suitable bearings 85 and driven directly from motor M by a belt 86 engaging a large pulley 87 keyed to the shaft 84 and a pulley 88 fixed to the motor shaft.

The shiftable pulley 76 insures smooth operation at all times. In other words, when a different bias angle is desired, framework F is shifted to the right or to the left about the pivot G. Pulley 79 thus moves also, and belt 72 consequently reaches the sheave 76 from a different angle, any variations of such angularity being automatically taken care of by yieldingly shiftable plates 78, as will be obvious.

Referring now to Figure 16, which particularly illustrates the manner in which the pivot G, base A, and framework F are associated, the frame F, similar to base A, includes longitudinal upper and lower rails 89 and 90 and projects through the space intervening between rails 1 and 2 of base A. A pair of spaced plates 91 connect, and are rigid with, the pair of rails 89 and 90. Similar plates 92 connect the rails 1 and 2 in the region of the pivot G, which passes through registering apertures in the several plates 91, 92, and is threaded at its opposite ends for receiving suitably retaining nuts g.

It may be mentioned that all weight and strain are removed from pin G for facilitating shifting movements of the frame F, the motor M, for convenience, being arranged on the lower plate 91, and threaded through a bracket 94 on rail 1 of frame A and having a hand or turning wheel 95 at its upper end, is a suitably elongated screw or pin 96 adapted for impingement at its lower end with, and upon the upper face of, a flat bar 97 for releasably retaining the frames A and F in angularly adjusted position. The bar 97, it may be added, is pivotally fastened at one end to one side of the frame F and normally flatwise abuts

at its opposite end upon a ledge or the like 98 on the frame A, as best seen in Figures 1, 6, 12, and 13, the pin 96 being readily manipulated from engagement with bar 97 for enabling a change 5 in the angularity or bias of frame F relatively to frame A.

Having particular reference now to Figures 1, 2, 17, 18, and 19, the mandrel B, as shown, is substantially a cantilever, and its frame or structure 6 at its forward end comprises a cross-member 99. Supported in advance of the structure 6 and over the table 10 by means of a control rod 100 and angular side-braces 101 suitably fixed to the mandrel-member 99, is a frusto-conical member or nose 102, which, with the oblique brace or side members 101, it may be here stated, and as presently more fully appears, function to spread or expand the cloth-tube a'' laterally and vertically, as it were, as indicated in Figure 2, thus opening the tube a'' just after it leaves the bin 12, so that the tube a'' advances smoothly on to the mandrel B with a minimum of friction.

Fixed to and upon and adjacent the opposite ends of the mandrel-beams or channels 6, are opposed outwardly presented rigid brackets 107, 111, supported by which in suitable spaced relation to the beams 6, are longitudinally extending shafts 103, which, in turn, support preferably fixed cylindrical members or rolls 104 in a plane disposed slightly below the plane of the lower flanges of the beams 6, as best seen in Figure 13.

Pivotedly supported on the brackets 107 and disposed upon one side of the mandrel B, are arms 107', which, in turn, normally support a cylindrical bar or tube 108 in a plane spaced upwardly from the mandrel structure B, as best seen in Figures 18 and 27.

The tube 108 is stationary or in fixed position during machine operation. However, the arms 107' may be swingably adjusted to selectively locate the tube 108 to meet the size requirements of any particular cloth-tube a''. To such end, the arms 107' are rigid with or fixed to a rod 109 extending longitudinally through, and supported by, the brackets 107, selected or proper positioning of the particular tube 108 being had manually and locking or retention thereof in such adjusted or selected position being accomplished by any suitable means, such, for instance, as the thumbscrew and bracket arrangement indicated at 110, Figure 1.

Extending through the brackets 111 upon the opposite side of the mandrel-frame 6, is a longitudinal rod 111', normally secured against rotation by any suitable means, such as set-screws threaded for rod-engagement in the brackets 111.

Pivotedly mounted on the rod 111' at suitably spaced intervals throughout its length, are arms 112, which support a cylindrical bar or tube 113, which is substantially a duplicate of tube 108, except that the tube 113 is readily swingable to selectively accommodate, and depending upon the circumferential dimension of, the particular cloth-tube a'' being cut. In other words, the tube 113, as best seen in Figures 18, 19, and 27, is normally yieldingly or resiliently biased outwardly from the center of the mandrel-structure 6 by means of springs 114 anchored at their opposite ends in the arms 112 and the fixed rod 111', as shown, the longitudinal tube 113 accordingly exerting opening or spreading tension upon the tubing a'' as the latter advances spirally toward the cutter D.

Hence, it will be obvious that the machine will

readily accommodate cloth-tubes of varying circumferential dimensions and that minor irregularities in a given length of tubing a'' are compensated for in a simple yet effective manner.

At their right-hand or forward end, the tubes or members 108 and 113 project beyond the cross-member 99 and, as best seen in Figures 1 and 17, are tapered and arcuated inwardly, as at 115, 115', respectively, for facilitating travel of the particular cloth-tube a'' smoothly onto the mandrel B, the cross-sectional shape or contour assumed by the particular cloth-tube a'' as it travels rearwardly of the machine on the mandrel B being indicated by broken lines in Figure 18 and full lines in Figure 27.

The entire cutting assembly D is so located upon the machine as to be surrounded by, or housed within, the particular cloth-tube a'' being cut, as is best seen in Figures 26 to 30, inclusive. As there shown, the cutting mechanism D includes a disc-shaped blade or cutter 116, which is removably mounted on the shaft of a suitable motor or other prime-mover 115' mounted on a suitable bracket 117 depending from a generally rectangular plate 118 shiftably supported in ways 119 secured to the frame 6.

Threaded at one end in a lug 120 depending from the plate 118, as best seen in Figure 28, and adjacent its opposite end being releasably or adjustably engaged by a set-screw 121 with an apertured block 122 fixed to frame 6, is a rod 123 for manual actuation for shifting the plate 118 for adjustably positioning the cutter 116 at any desired location within the confines of an opening 124 provided in a suitable rigid plate 125 fixed to and upon the under side of frame 6 and suitably elongated to extend at its opposite ends and longitudinally of frame 6 a relatively short distance beyond the margins of diagonal frame F, as best seen in Figure 1.

In addition, the angularity of the blade or cutter 116 relatively to the frame 6 or plate 125 for varying the angle of the bias cut is independently adjustable, and, for such purpose, the bracket 117 is preferably suitably fixed to a preferably angularly-shaped plate 126, which is mounted for oscillatory movement about a pivot pin 127 carried by the slide 118 and provided, as best seen in Figure 26, with an arcuate slot 128 for accommodating a bolt-and-washer assembly 129 for retaining the plate 126 and the motor and blade supporting bracket 117 in swung or oscillated position. A suitable link 130 connects the plate 126 pivotally with an arm of a bell-crank-lever 131 pivoted, as at 132, to the under side of the slide 118, and adapted at its other or pointer-arm to traverse an arcuate index 133 substantially defined by a correspondingly shaped slot 134 in the plate 118, an accommodating recess, as at 135, for such purpose being formed in the depending lug 120, and the blade or cutter 116 being locked in a selected or desired position by means of a thumb-and-screw assembly or the like 136.

Fixed, as by screws 131, to the vertically depending flange of angle bracket 117, as best seen in Figure 27, is an angle-member 138 having a relatively wide rectangular base-portion 140 equipped with a smooth, flat under face and formed with an arcuate groove 141 for accommodating a portion of the peripheral cutting edge of the blade 116, such base-portion 140 being tapered and rounded, as indicated at 142, so that any wrinkling or friction that may develop in the particular cloth-tube a'' as it approaches the blade 116 is eliminated.

The endless belt assembly H, as shown, is supported on the framework F and is thus disposed diagonally with respect to the mandrel B, and it may be here mentioned that, in the successful operation of the machine at high speeds, it is extremely important that any transverse shifting of the belt be entirely obviated.

With particular reference now to Figures 1, 3, 4, 6, and 10, suitably mounted for rotation on, and disposed adjacent the opposite ends of, the framework F, are parallel driving and driven rollers 143, 144, respectively, circumferentially provided centrally intermediate their ends with registering V-grooves 145, and reeved over and around the driving and driven rollers 143, 144, is a suitable endless belt 146 permanently provided centrally on its under face and throughout its length with a relatively narrow V-strip 147 for fitting the grooves 145 of the rollers 143, 144. 15 And preferably also mounted for rotation on the frame F intermediate the rollers 143, 144, and the upper and lower runs of the belt 146, are guide-pulleys 148, 149, correspondingly circumferentially grooved, as at 150, for engagingly accommodating the V-strip 147 of the belt 146, which, through the engagement of its V-strip 147 with the pulleys 148, 149, and rollers 143, 144, is definitely retained from any sidewise or transverse slippage or movement with respect to the rollers 143, 144, during machine operation, a supplemental roller 152 disposed directly under the guide-pulley 149 for engagement against the under side of the lower run of the belt 146 functioning as a holding-member for eliminating any tendency of the V-strip 147 to leave or "jump" the groove of roller 144.

As best seen in Figure 10, the driven roller 144, guide-pulley 149, and belt securing roller 152 are mounted on a platform 153 hingedly connected, as at 154, to a cross-member 155 fixed on the framework F, the platform 153 at its free end carrying or supporting a relatively heavy weight 156. Hence, obviously, the endless belt 146 is maintained sufficiently taut, under the gravity pull of the weight 156, throughout machine operations.

As best seen in Figures 4, 10, and 11, a rope or other flexible member 160 has one end fixed to the platform 153 and is then reeved over a pulley 161 supported on a rigid upright 162 of the framework F, the member 160 then passing through an opening provided for the purpose in the platform 153 for connection or attachment at its opposite end, as at 163, to a sheave 164 fixed on a shaft 165 supported for rotation in bearings 166, as best seen in Figure 11. Also fixed on shaft 165, is a somewhat smaller sheave 167, to which another flexible member 168 is suitably attached at one end, as at 169, the member 168 being fixed at its opposite end to the lower extremity of a hand lever 170 pivoted intermediate its ends, as at 171, on frame F. Consequently, pulling strain on the opposite or handle-end of lever 170 will swingably elevate the platform 153 and thereby relieve the tautness of belt 146 while the machine is idle or while the machine is being prepared for operation.

More specifically, when the belt 146 is in so-called taut condition, as during machine operation, the lever 170 is swung to the left, as indicated in Figure 4, and pull on platform 153 through member 168 relieved or removed. Obviously, shifting the lever 170 to the right will, 70 through pull exerted through member 168, ele-

vate the platform 153 and, consequently, as previously observed, relieve the tautness of the endless belt 146. Any suitable means, such, for instance, as a pawl-and-ratchet, or the disposition of a pin (not shown) through an apertured ear 172 on the lever 170 and also through a selected perforation 173 in the framework F will easily retain the lever 170 in a selected swung position with pull on platform 153 correspondingly selected.

As best seen in Figure 4, the shaft 174 of the belt-driving roller 143 is rotatably mounted or journaled at its opposite ends in a pair of suitably spaced side frames 175 forming substantially a part of the framework F and which also support gearing L of the winding assembly K of the machine.

Fixed to and upon the shaft 174, is a sprocket 176, engaging with which is a suitable chain 177, in turn, driven by a sprocket 178 fixed to the shaft 80 driven through pulley-belt-and-shaft connection with the motor M, as previously mentioned.

Also fixed on shaft 174 adjacent the sprocket 176, is a gear 179, which meshes with an idler 180 fixed on a cross-shaft 181 suitably journaled in the side-frames 175, gear 180, in turn, meshing with a gear 182 fixed on a shaft 183 also journaled in the side-frames 175. Fixed on shaft 183, is a winding roll 184, cooperable with which is a lower winding roll 185 fixed on a shaft 189 likewise journaled in the side-frames 175, as also indicated in Figure 7. And, as shown in Figures 5 and 6, a relatively smaller gear 186 is fixed on the shaft 183 for meshing engagement with an idler 187 journaled on a stub-shaft 188, and fixed on the shaft 189 of the lower winding roll 185, is a similar gear 190, which also meshes with the idler 187. Thus, the upper and lower or companion rolls 184 and 185 are rotatably actuated at the same speed and in the same direction.

Preferably a belt-and-pulley assembly 191, best seen in Figure 5, is provided for enabling convenient manual rotation of the winding rolls 184 and 185 while preparing the machine for operation, as will be well understood, the side-frames 175 being preferably joined and braced by cross-rods 192, 193. It may be observed here that, as best seen in Figure 6, the guide-pulley 148 is preferably journaled in suitable bearings mounted on a bracket 194 preferably integral with the frames 175, a winding-roll protecting-member or rod 195 having its ends fixed in the frames 175 and disposed in suitably spaced relation over the rolls 184, 185, and an idler roll 196 being preferably journaled on the shaft 181 intermediate the frames 175. It may also be observed here that the lower pulley 197 of the winding-roll manual actuating-means is fixed on a stub-shaft 198 supported in bearings 199 on the frames 175, while the upper pulley 200 of such actuating means is preferably fixed to winding-roll shaft 189.

As the bias-cut cloth a^3 leaves the machine proper, the same is preferably wound on a tube 201, as indicated in Figure 37, readily removable from the machine. For such purpose and as shown especially in Figures 4 to 8, both inclusive, the side-frames 175 have registering rearwardly presented extensions 175' provided upon their upper surface with co-operable slide-ways 202, shiftable in which relatively to the rolls 184, 185, is a pair of angle-blocks or members 203 provided or formed, as best seen in Figure 9, with registering sockets or seats 204 providing a bear-

ing for the end of a removable mandrel 205, around or upon which a tube 201 of required length may be sleeved.

Journaled on the shaft 189 of the lower winding roll 185, are sheaves 206, reeved over which are suitable flexible members 207 each having an end secured to a pin or stud 208 fixed on a block 203 and its other end engaged with a relatively heavy cross-weight 209, which function to shiftable maintain the tube 201 firmly against the winding rolls 184, 185, during the winding thereon of the bias-cut strips a^3 as the cloth emerges or is delivered from the machine.

And attached to additional pins or studs 210 also fixed in the blocks 203, are flexible members 211, which are first reeved over pulleys 212 suitably journaled on the frame-extensions 175' and then are suitably attached, as at 213, to sheaves 214 fixed on a rock-shaft 215 supported in suitable bearings 216 on the frame-extensions 175'. A relatively smaller pulley 217 is fixed on the rock-shaft 215, and hingedly attached, as at 218, to an arm 219, rigid with a side-frame 175, is a treadle 220, and connecting the treadle 220 with the pulley 217, is a suitable flexible member 221. Obviously, therefore, depression of treadle 220 will shift the blocks 203 and the supported mandrel 205 and its roll 201 away from the winding rolls 184, 185, for convenient replacement removal from the machine, the free shifting of the roll 201 relatively to the winding rolls 184, 185, also readily permitting the winding of the bias-cut cloth a^3 on the tube 201 to the desired diametrical dimension or thickness.

As presently more fully appears, the endless belt 146 performs the dual function of drawing or delivering or feeding the cloth-tube a^3 to the cutter-assembly D for bias-cutting and then delivers or feeds the bias-cut strip a^3 , without any stretching whatever of the cloth, to the winding-up mechanism K. It is hence very desirable, if not really essential, that the upper run of the belt 146 be additionally maintained in a taut condition against the mandrel B and plate 125 as it passes thereunder. For such purpose, a pair of angle members 222 extend longitudinally along the base A adjacent the roll 103 of the mandrel B and are pivotally supported at an end, as at 223, on the respective uprights 105, 106, as best seen in Figures 1, 2, 13, 25, 26, and 27. Each angle 222 carries a belt-engaging member 224 nicely and smoothly rounded, as at 226, and suitably cut-out or grooved, as at 227, for accommodating the V-strip 147, each angle member 222 being pivotally attached at its opposite end, as at 228, to a block or member 229 adjustable lengthwise slidably in a vertically disposed way 230 fixed on an upright 231 of the framework A. Fixed at an end to a lateral extension of each block or slide 229, is a suitable flexible member 232, which is first reeved over a sheave 233 supported for rotation on upper frame-rail 1 and then around a second sheave 234 mounted for rotation on lower frame-rail 2, as best seen in Figures 2 and 17. The flexible member 232 on the one or so-called far side of the machine, as viewed in Figure 17, is attached at its opposite end to its co-operable sheave 234, which the flexible member 232 on the opposite or near side of the machine, after passing under its co-operable sheave 234 and thence under a supplemental sheave 235, is fastened, as at 236, to a hand lever 237 pivotally attached at an end, as at 238, on the lower frame-rail 2, the sheave 234 on the far side of the machine and the sheave 235 on the near side of the

machine being fixed or mounted on a common shaft 239 suitably journaled in the machine framework A.

When lever 237 is disposed to the left, as indicated in Figure 2, the tensioning members or beams 224 are elevated to occupy the respective positions thereof illustrated in Figure 27, the tension on the upper run of the belt 146 being thereby increased for cloth engagement, any suitable pawl-and-ratchet arrangement or other suitable means, such, for instance, as the means indicated at 240 in Figure 2, being employed for maintaining the hand-lever 237 in its swung position to the left, while the machine is in operation. When pivotally shifted to the right, the hand-lever 237 permits the blocks or slides 229 and the angles 222 and supported tension-beams 224 to drop by gravity a predetermined distance for relieving the belt 146 of such extra tension.

Suitably pivoted to the cross-member 193 of the framework A, as best seen in Figure 4, is a clutch-actuating pedal 241 having suitable connection, as by means of a suitable flexible member 242 reeved over suitable guide-pulleys 243 and 244, with an arm or lever 245 adapted, upon movement in one direction, for shifting a clutch-member on the pulley 87 for driven connection between shaft 84 and the driving mechanism L with the motor or other prime-mover M, previously mentioned, for setting the machine into operation.

When the machine is idle, the pedal 241 is yieldingly held in elevated position by means of a suitable spring 246 suitably anchored at an end to the frame F and at its opposite end to the lever 245, as shown. Obviously, if the operator elects so to do, the clutch mentioned may be simply operated by manipulation of the lever 245, and it may be here mentioned that the motor mechanism is controlled by a suitable switch (not shown), an independent switch (also not shown) being provided for closing the circuit to the cutter mechanism D.

The operation of the machine has been set forth at intervals in the foregoing description. Summarizing—

Assuming that the switches of the actuating and cutting motors are in "off" position, that the cloth-tube a'' has been properly positioned in the bin 13, and that the hand-levers 170 and 237 are in released position to the right, the operator pivotally or swingably first adjusts the movable framework F relatively to the main or fixed framework A at such selected angle as will produce the desired width of cloth cut on the bias, then depresses treadle 59 and manipulates hand-wheel 32 until the pointer 28 indicates approximately the required speed of rotation of the cloth-unwinding turntable 11, sets the cutter-assembly D and its blade 116 in proper co-ordination with belt 146, and suitably expands and tensions the tube a'' for engaging the tube a'' with the belt 146 and flat plate 125, the latter as best seen in Figure 27.

The operator, now releasing treadle 59, manually disposes the cloth-tube a'' along mandrel B until its leading margin is positioned at or adjacent the groove 141 in the foot member 138 and in approximate cutting engagement with the rotary cutter 116. Inasmuch as the belt 146 is at this time in a relatively sagging or released condition, and inasmuch as the aperture 124 in plate 125 permits convenient manipulation of the cloth-tube a'' , an experienced operator may

properly position the leading margin of the cloth-tube a'' in a very brief period of time.

Assuming now that the cloth-tube a'' has been so positioned with respect to the cutter 116 and that the levers 170 and 237 have been manipulated to the left and the belt 146 as a whole and also its upper run suitably tensioned, the switches controlling the main motor M and cutter motor circuits are shifted to "on" position, when the operator, either manually or through foot-actuation of the pedal 241, shifts the clutch lever 245 to the left, thereby setting and continuing the machine in operation until a sufficient length of bias-cut cloth a^3 has been produced to reach the winding mechanism K. The clutch lever 245 is now released, and assuming that a proper tube 201 has been positioned on the mandrel 205, the cut material a^3 is at its free margin manually disposed for winding about the tube 201, the treadle 228 being depressed during such operation for spacing the roll 205 and supported tube 201 from the winding rolls for conveniently disposing the bias-cut cloth in winding position upon the tube 201.

The machine is now ready for continuous operation, and, upon actuation again of the clutch lever 245 and consequent closing of the circuits of the driving and cutter motors, will function smoothly, its capacity being limited only by the amount of material a'' which the bin 13 is capable of containing. Obviously an indefinite number of identical rolls of material a may be successively bias-cut without further adjustments, except such readjustments of the cloth-tube unwinding rate, which may be very conveniently had by the means described while the machine is in operation, the endless belt 146 functioning, as has been previously stated, in first spirally drawing or feeding the cloth-tube a'' in a straight path or line of travel over the mandrel B to the cutting blade 116 and then advancing and delivering the bias-cut cloth a^3 over the frame F and in a line of travel oblique to the mandrel B to the winding mechanism K, without any stretching whatever either of the straight-cut cloth a'' or the bias-cut cloth a^3 .

Obviously, while not here shown, suitable means may be employed for maintaining the clutch pedal 241 or the clutch lever 245 in circuit closing position for enabling the operator to give his entire time and attention to different parts of the machine during operation or actuation, unwinding of the cloth-tube a'' being readily interrupted at any time by depression of treadle 59 or treadle 98, as previously described.

The cutting assembly D, as particularly seen in Figure 27, is enclosed within the tubing a'' , safeguarding the operator as to injury of his hands and fingers, and the various permitted adjustments of machine parts permit precise positioning of the cutter assembly D, the belt 146 being protected by plate 149 from engagement with the blade or cutter 116 and, when tensioned, as described, being in frictional or drawing contact with the cloth at all points except in the particular cutting area defined by such plate 149, the bottom or under surface of which, it might be stated, is preferably highly polished, so that wear on the belt 146 is negligible, actual minute clearance obtaining between belt 146 and plate 149 during machine operation.

The machine has been found to be exceedingly efficient in the performance of its intended functions, and it is to be understood that changes and

modifications in the form, construction, arrangement, and combination of the several parts of the machine may be made and substituted for those herein shown and described without departing from the nature and principle of my invention.

Having thus described my invention, what I claim and desire to secure by Letters Patent is:

1. A bias-cutting machine including, in combination, a cutter, a mandrel, and means comprising an endless belt arranged for travel in a linear path extending in advance of, under, and rearwardly of, the cutter and mandrel for feeding the uncut cloth to, and shifting the cut cloth from, the cutter.

2. A bias-cutting machine including, in combination, a cutter, a mandrel, and means comprising an endless belt reeved over and around spaced rollers for travel in a linear path extending in advance of, transversely under, and rearwardly of, the cutter and mandrel for feeding the uncut cloth to the cutter along one line of travel and for carrying the cut cloth from the cutter along a different line of travel angularly disposed to the first line of travel.

3. A bias-cutting machine including, in combination, a mandrel, a cutter disposed intermediate the length and in the plane of the mandrel, and means comprising an endless belt reeved over and about spaced rollers for travel in a linear path extending in advance of, transversely under, and rearwardly of, the cutter for shifting the cloth spirally in uncut tube form along the mandrel to and about the cutter and then shifting the cut cloth in strip form from the mandrel.

4. A bias-cutting machine including, in combination, a cutter, a mandrel, and means comprising an endless belt for feeding the uncut cloth in tube form along and about the mandrel and also enclosingly about the cutter for slitting engagement by the cutter with the lower run of the cloth-tube during feeding thereof.

5. A bias-cutting machine including, in combination, a cutter, a mandrel, means comprising an endless belt for feeding a tubiform cloth along and about the mandrel and also enclosingly about the cutter, and means for spacing the lower run of the moving cloth from the belt for slitting engagement therewith by the cutter.

6. A bias-cutting machine including, in combination, a cutter-assembly comprising a rotary blade, a mandrel, means comprising an endless belt for feeding a tubiform cloth along and about the mandrel and also enclosingly about the cutter-assembly, and a plate forming part of the cutter-assembly and slotted for blade-accommodation for elevating the lower run of the moving cloth from the belt for slitting engagement therewith by the cutter.

7. A bias-cutting machine including, in combination, a mandrel, a cutter disposed intermediate the length and in the vertical plane of the mandrel, a rotary table for supporting at an end of the mandrel in layerwise formation a length of tubiform cloth for cutting, and means comprising an endless belt adapted for travel in a linear path transversely of the mandrel and cutter for shifting the tubiform cloth from the table and to and about the mandrel and enclosingly about the cutter for slitting.

8. A bias-cutting machine including, in combination, a mandrel structure, a cutter disposed intermediate the length and within the mandrel-structure, a rotary table for supporting at an end of the mandrel in layerwise formation a length of tubiform cloth for slitting, and means com-

prising an endless belt reeved over and around spaced rollers for travel in a linear path crosswise of the mandrel and cutter for shifting the tubiform cloth from the table and spirally along and about the mandrel to and about the cutter for slitting and then shifting the slit cloth angularly from the mandrel.

9. A bias-cutting machine including, in combination, a mandrel structure, a cutter disposed intermediate the length and within the mandrel-structure, a rotary table for supporting at an end of the mandrel in layerwise formation a length of tubiform cloth for slitting, means comprising an endless belt reeved over and about spaced rollers angularly located on opposite sides of the mandrel for travel in a straight path in advance of, crosswise under, and to the rear of, the mandrel and cutter for shifting the tubiform cloth from the table and spirally along and about the mandrel to and about the cutter for slitting the lower run thereof and then shifting the cut cloth from the mandrel, and means for actuating the belt and table in synchronism.

10. A bias-cutting machine including, in combination, a mandrel structure, a cutter disposed intermediate the length and within the mandrel-structure, a rotary table for supporting at an end of the mandrel in layerwise formation a length of tubiform cloth for slitting, means comprising an endless belt adapted for travel in a linear path crosswise of and under the mandrel and cutter for feeding the tubiform cloth from the table and to and spirally about the mandrel to and about the cutter for slitting the lower run thereof and then shifting the cut cloth angularly from the mandrel, means for actuating the table and belt, and means for selectively indexing the rotary speed of the table relatively to the longitudinal speed of the traveling belt.

11. A bias-cutting machine including, in combination, a cutter, a mandrel, a traveling endless belt, and means comprising shiftable members extending longitudinally of the mandrel for engaging the upper run of the belt for tensioning the belt for engaging the uncut cloth for shifting the cloth along the mandrel to the cutter and the cut cloth from the cutter.

12. A bias-cutting machine including, in combination, a frame, a mandrel-structure comprising a pair of spaced longitudinally extending rolls on the frame, a rotary cutter disposed on the mandrel-structure intermediate said rolls, a traveling endless belt, a pair of members mounted shiftably on the frame in spaced relation to the rolls, and means for shifting said members for tensioning the upper run of the belt therebetween and the rolls for engaging the uncut cloth for shifting the cloth along the mandrel-structure to the cutter and the cut cloth from the cutter.

13. A bias-cutting machine including, in combination, a frame, a mandrel-structure comprising a pair of spaced longitudinally extending rolls on the frame, a rotary-cutter disposed on the mandrel-structure intermediate said rolls, a flat plate disposed on the mandrel-structure in underlying relation to, and slotted for accommodating, the cutter, a traveling endless belt, a pair of members mounted shiftably on the frame in spaced relation to said rolls, and means for shifting said members for engaging the upper run of the belt with said plate for slitting engagement by the cutter.

14. A bias-cutting machine including, in combination, main and auxiliary framework, a man-

dreel-structure on the main framework, a cutter mounted on the mandrel-structure, means comprising an endless belt mounted for travel on the auxiliary framework with its upper run traveling under the cutter, and means for longitudinally tensioning the belt for engaging the cloth for feeding the same to the cutter.

15. A bias-cutting machine including, in combination, main and auxiliary framework, a mandrel-structure on the main framework, a cutter mounted on the mandrel-structure, spaced rolls mounted for rotation on the auxiliary framework, an endless belt traveling over said rolls with its upper run under the cutter, and means for shifting one of said rolls relatively to the other for longitudinally tensioning the belt for engaging the cloth for feeding the same along the mandrel-structure to the cutter for cutting.

16. A bias-cutting machine including, in combination, a main framework, an auxiliary framework angularly disposed to the main framework, a cantilever mandrel-structure fixed longitudinally on the main framework, a cutter on the mandrel-structure, winding mechanism mounted on, and at an end of, the auxiliary framework, and means comprising an endless belt mounted for travel over the auxiliary framework and under the cutter for feeding a tubiform cloth over and spirally along the mandrel-structure to the cutter and the cut cloth from the cutter over the auxiliary framework to the winding mechanism.

17. A bias-cutting machine including, in combination, a main framework, an auxiliary framework, a mandrel-structure fixed on the main framework, a cutter disposed on and within the mandrel-structure, and means comprising an endless belt mounted for travel in a linear path on the auxiliary framework for feeding uncut cloth along and about the mandrel-structure to and about the cutter and from the cutter over the auxiliary framework, the auxiliary framework being shiftable relatively to the main framework for varying the angularity of travel of the belt relatively to the mandrel-structure.

18. A bias-cutting machine including, in combination, a main framework, an auxiliary framework, a mandrel-structure on the main framework, a cutter on the mandrel-structure, and means including an endless belt mounted for travel on the auxiliary framework in a linear path transversely of and under the mandrel and cutter for feeding uncut cloth along and about the mandrel-structure to and about the cutter for slitting of the lower run thereof, the cutter being shiftable relatively to the mandrel-structure for varying the bias angle of the cut cloth.

19. A bias-cutting machine including, in combination, a main framework, an auxiliary framework, a mandrel-structure fixed on the main framework, a cutter pivoted on the mandrel-structure for angular adjustment thereof, means including an endless belt mounted for travel on the auxiliary framework in a linear path transversely of and under the mandrel and cutter for feeding the uncut cloth along and about the mandrel-structure to and about the cutter for slitting of the lower run thereof, and means for indexing the bias-cutting angularity of the cutter relatively to the mandrel-structure.

20. A bias-cutting machine including, in combination, a framework, spaced rollers on the framework, a cutter intermediate the rollers, an endless belt traveling over the rollers for feeding cloth to the cutter for slitting, and

means for retaining the belt from transverse slippage on the rollers.

5 21. A bias-cutting machine including, in combination, a framework, spaced circumferentially grooved rollers on the framework, a cutter intermediate said rollers, an endless belt traveling over the rollers for feeding cloth to the cutter for slitting, and means comprising a projection disposed longitudinally on, and projecting from the inner face of, the belt for fitting the grooves in said rollers for retaining the belt from transverse slippage on the rollers.

10 22. A bias-cutting machine including, in combination, a framework, spaced circumferentially grooved rollers on the framework, a cutter intermediate said rollers, circumferentially grooved guide-pulleys also intermediate the rollers, an endless belt traveling over the rollers for feeding the cloth to the cutter for slitting, and means comprising a V-strip disposed longitudinally on, and projecting from the inner face of, the belt for engaging the grooves in the rollers and pulleys for retaining the belt from transverse slippage on the rollers.

15 23. A bias-cutting machine including, in combination, a framework, spaced circumferentially grooved rollers on the framework, a cutter intermediate said rollers, an endless belt traveling over the rollers for feeding the cloth to be cut to the cutter, and means for retaining the belt from transverse slippage on the rollers, said means comprising circumferentially grooved guide-pulleys disposed intermediate said rollers, a V-strip disposed longitudinally on, and projecting from the inner face of, the belt for engaging the grooves in the rollers and pulleys, and flat-faced pulleys for belt-engagement in opposed relation to said grooved pulleys.

20 24. A bias-cutting machine including, in combination, main and auxiliary framework, a mandrel-structure on the main framework, a cutter mounted on and within the mandrel-structure, winding mechanism for the cut cloth, and means comprising an endless belt arranged on the auxiliary framework for travel in a linear path transversely of and under the mandrel-structure for shifting uncut cloth to and about the cutter for slitting and the slit cloth from the cutter to the winding means.

25 25. A bias-cutting machine including, in combination, a framework, a cutter, a pair of winding rolls for the cut cloth, means for shifting uncut cloth to the cutter for slitting and the slit cloth from the cutter to the winding rolls, a tube-supporting mandrel on the machine for taking the cut cloth from the rolls, and means for retaining the mandrel in operative cloth-receiving engagement with the rolls.

30 26. A bias-cutting machine including, in combination, a framework, a cutter, winding means comprising a rotary shaft for the cut cloth, means comprising an endless belt arranged for travel on the framework for shifting uncut cloth to the cutter for slitting and the slit cloth from the cutter to the winding means, said shaft being bodily shiftable relatively to the belt for accommodating increasing diametrical dimension of the wound cloth, and means comprising a weight depending from said shaft for tensioning the cut cloth during winding thereof upon said shaft.

35 27. In a bias-cutting machine, a mandrel for receiving the cloth in tubular form for cutting, a cutter on the mandrel, means for shifting the cloth in tubular form over and along the mandrel to and about the cutter, and means for expand-

75

ing the tube about the mandrel and cutter during shifting.

28. In a bias-cutting machine, a mandrel for receiving the cloth in tubular form for cutting, a cutter on the mandrel, means for shifting the cloth in tubular form over and along the mandrel to and about the cutter, and means comprising spaced members disposed longitudinally of, and in spaced relation to, the mandrel for expanding the tube about the mandrel and cutter during shifting, one of said members being swingably shiftable relatively to the other.

29. In a bias-cutting machine, a mandrel for receiving the cloth in tubular form for cutting, a cutter on the mandrel, means for shifting a cloth in tubular form over and along the mandrel to and about the cutter, and means comprising a plurality of spaced elongated members disposed longitudinally of, and in spaced relation to, the mandrel for expanding the tube about the mandrel and cutter during shifting, one of said members being yieldingly swingable relatively to the mandrel.

30. A bias-cutting machine including, in combination, a mandrel, a cutter on, and disposed in the plane of, the mandrel, unwinding mechanism comprising a rotary table for supporting a length of tubiform cloth for cutting, winding mechanism for the cut cloth, means comprising an endless belt arranged for travel in a linear path transversely of and under the mandrel for shifting the tubiform cloth from the table and along and about the mandrel and to and about the cutter for slitting the lower run thereof and then shifting the cut cloth from the cutter to the winding mechanism, and means for actuating the unwinding mechanism, the winding mechanism, and the belt in synchronism.

31. A bias-cutting machine including, in combination, main framework, auxiliary framework angularly disposed with relation to the main framework, a mandrel-structure on the main framework, a cutter on the mandrel-structure, unwinding mechanism comprising a rotary table for supporting adjacent the mandrel-structure a length of tubiform cloth for cutting, winding mechanism at the discharge end of the auxiliary framework for the cut cloth, means comprising an endless belt arranged for travel on the auxiliary framework for shifting the tubiform cloth from the table and along and about the mandrel and to and about the cutter for slitting the lower run thereof and then shifting the cut cloth from the mandrel to the winding mechanism, and means for actuating the unwinding mechanism, the winding mechanism, and the belt.

32. A bias-cutting machine including, in combination, a mandrel, a cutter on, and disposed in the plane of, the mandrel, unwinding mechanism comprising a rotary table for supporting a length of tubiform cloth for cutting, winding mechanism for the cut cloth, means comprising an endless belt arranged for travel in a linear path transversely of and under the mandrel and cutter for shifting the uncut cloth from the table and along and about the mandrel and to and

about the cutter for slitting the lower run thereof and then shifting the cut cloth from the mandrel to the winding mechanism, means for actuating the unwinding mechanism, the winding mechanism, and the belt, and means for selectively indexing the speed of movement of the unwinding mechanism.

33. A bias-cutting machine including, in combination, a mandrel, a cutter on, and disposed in the plane of, the mandrel, unwinding mechanism comprising a rotary table for supporting a length of tubiform cloth for cutting, winding mechanism for the cut cloth, means comprising an endless belt arranged for travel in a linear path transversely of and under the mandrel and cutter for shifting the uncut cloth from the table and along and about the mandrel and to and about the cutter for slitting the lower run thereof and then shifting the cut cloth from the mandrel to the winding mechanism, means for actuating the unwinding mechanism, the winding mechanism, and the belt, means for visibly indicating the speed of the unwinding mechanism relatively to the speed of the winding mechanism, and means for adjustably regulating the speed of the unwinding mechanism in relation to the speed of the winding mechanism.

34. A bias-cutting machine including, in combination, a framework, a mandrel-structure fixed on the framework, a cutter-assembly on the mandrel-structure, and means comprising an endless belt arranged for travel in a linear path transversely of and under the mandrel structure and cutter assembly for feeding a tubiform cloth along the mandrel-structure to and about the cutter-assembly for slitting into strip-form, the cutter-assembly being shiftable relatively to and within the length of the mandrel-structure for varying the width of the cut strips.

35. A bias-cutting machine including, in combination, a main framework, an auxiliary framework, a mandrel-structure fixed on the main framework, a cutter-assembly on the mandrel-structure, and means comprising an endless belt mounted for travel on the auxiliary framework in a linear path transversely of and under the mandrel-structure and cutter-assembly for feeding uncut cloth along and about the mandrel-structure and to and about the cutter for slitting the lower run thereof and from the cutter over the auxiliary framework, the auxiliary framework being shiftable relatively to the main framework for varying the angularity of travel of the belt relatively to the mandrel-structure and the cutter-assembly being shiftable relatively to the mandrel-structure for varying the width of the cut cloth.

36. A bias-cutting machine including, in combination, a fixed mandrel, a cutter located intermediate the length and in the vertical plane of the mandrel, and means for shifting the cloth spirally in uncut tube form along and about the mandrel and to and about the cutter for slitting engagement by the cutter with the lower run of the cloth tube during shifting thereof.

EDWARD B. CASE.
